UNITED STATES PATENT OFFICE.

AMY L. HURLSTONE-JONES, OF LONDON, ENGLAND.

APPARATUS FOR PLAYING GAMES AND FOR PHYSICAL CULTURE.

1,372,351.

Specification of Letters Patent. Patented Mar. 22, 1921.

Application filed July 16, 1919. Serial No. 311,248.

To all whom it may concern:

Be it known that I, AMY LILIAN HURLSTONE-JONES, a subject of the King of England, residing at London, England, have 5 invented certain new and useful Improvements in and Relating to Apparatus for Playing Games and for Physical Culture, of which the following is a specification.

This invention relates to toys and physical culture devices which may be employed 10 to play various games as well as for the development of the muscles and consists of an animal's head provided with a flexible neck containing one or more springs secured 15 to a board or plate of wood, leather or other suitable material provided with straps or equivalent means by which it may be secured to any suitable object such as the back of a chair, the foot-board of a perambulator or 20 the like on or in which a child may sit and pretend she is driving a horse or other animal. The improved toy may in some cases be secured to another child.

In some cases the neck may be provided 25 with a squeaker or like device adapted to make a noise similar to that of the animal represented when the reins are pulled.

According to a modified construction the board or plate may be dispensed with and 30 the neck connected directly to a model horse, provided with proper saddle and stirrups, in which case stronger springs may be employed in the neck so as to exercise the arm muscles when the reins are pulled.

35 I will now proceed to more particularly describe my invention with the aid of the accompanying drawings in which:—

Figure 1 is a side elevation of a horse's head and neck embodying the present improvements, part of which is torn away to 40 show its construction.

Fig. 2 is a perspective view showing the improved toy strapped to the back of a chair and a child playing with it.

45 Fig. 3 is a perspective view of a child's perambulator with the improved toy clamped to the front thereof.

Fig. 4 is a side elevation of a rocking horse having a head constructed according 50 to the present invention, and

Fig. 5 is a side elevation of the improved head with part of the neck torn away, illustrating a modified construction.

According to the construction illustrated 55 by Figs. 1 and 2 the animal's head *a* is provided with a flexible neck *b* of plush or other

suitable fabric within which is situated a spring *c* which connects the said head with a board or plate *d* of wood or other suitable material. The board *d* is mounted on a 60 backboard, plate or sheet *e* of leather or other suitable material which is provided with straps *f* having buckles or other suitable fastenings (not shown) by means of which the animal's head may be secured to the 65 back of a chair *g*.

The animal shown in the drawings is provided with a bit *h* bridle *i* and reins *j* which are held by the child playing with it, who causes the head to move to the right or left, 70 or up and down when she pulls the reins. A squeaker *s* may be secured to the board *d*, the bellows of which are compressed by the part *t* when the horse's head is moved by the 75 reins.

According to the construction shown in Fig. 3 the backboard *e* is provided with a clamp *k* by means of which it may be attached to the foot of the perambulator *l*. With this arrangement the child is enabled 80 to play at horses while being wheeled about.

In Fig. 4 the improved head is applied to a rocking horse and affords the child an opportunity to exercise her muscles at the same time as she is playing.

According to this construction, the head is provided with a stem *m* adapted to slide 85 in a socket *n* and is maintained in its outward position by a spring *o* of suitable strength which is compressed when the child 90 pulls the reins *j*.

According to the modification illustrated by Fig. 5 the socket *n* is formed in the head and the stem *m* is mounted on a block *p* attached to the body of the animal by strong 95 flat springs *q* which enable the head to be pulled to the right or to the left when it is desired to exercise the muscles of one arm at a time. This construction is also adapted for use with apparatus for teaching older 100 children to ride horse-back.

Although this invention has been described in conjunction with a horse's head it is obvious that the heads of other draft animals can be substituted in which case a 105 device of known construction adapted to make an appropriate noise may be situated in a position to be operated when the reins are pulled.

I claim:

1. Improvements in apparatus for playing games and for physical culture, comprising

ing an animal's head, a flexible neck, a block, a resilient element within said neck connecting said head to the aforesaid block, means of securing said block to a convenient support and reins connected to the sides of the animal's head to enable it to be moved against the resistance of the resilient element, substantially as set forth.

- 5 2. Improvements in apparatus for playing games and for physical culture, comprising an animal's head, a flexible neck, a block, a stem on said head, a socket formed in said block for said stem to slide in, a spring to urge said stem in an outwardly direction, means of securing said block to a convenient support and reins connected to the sides of the animal's head to enable it to be moved against the resistance of the aforesaid spring substantially as set forth in the specification.
- 10 3. Improvements in apparatus for playing games and for physical culture, comprising an animal's head, a block, a stem on one of these parts, a socket formed in the other for said stem to slide in, a flexible neck, a spring-controlled coupling connecting said block to a plate, a spring to urge said head in an outwardly direction, means of securing said plate to a convenient support and reins connected to the sides of the animal's head to enable it to be moved against the resistance of the aforesaid springs, substantially as set forth in the specification.
- 15 4. Improvements in apparatus for play-

ing games and for physical culture, comprising an animal's head, a flexible neck, a block, a resilient element within said neck connecting said head to the aforesaid block, a squeaker between the aforesaid head and block and in a position to be operated when the head is moved, means of securing said block to a convenient support and reins connected to the sides of the animal's head to enable it to be moved against the resistance of the aforesaid spring, substantially as set forth in the specification.

5. Improvements in apparatus for playing games and for physical culture, comprising an animal's head, a block, a stem on one of these parts, a socket formed in the other for said stem to slide in, a flexible neck, the body of an animal, a spring-controlled coupling connecting said block to said body, a spring to urge said head in an outwardly direction, and reins connected to the sides of the animal's head to enable it to be moved against the resistance of the aforesaid springs, substantially as set forth in the specification.

In testimony whereof I have signed my name to this specification in the presence of two subscribing witnesses.

AMY L. HURLSTONE-JONES.
